UNITED STATES PATENT OFFICE.

CHARLES C. HARPER, OF ELMIRA, NEW YORK, AND JOHN HARPER, OF DUNCANNON, PENNSYLVANIA.

BLOCK SYSTEM.

No. 855,571.

Specification of Letters Patent.

Patented June 4, 1907.

Application filed March 23, 1907. Serial No. 364,138.

To all whom it may concern:

Be it known that we, CHARLES C. HARPER and JOHN HARPER, citizens of the United States, residing at Elmira, in the county of Chemung and State of New York, and Duncannon, county of Perry, State of Pennsylvania, respectively, have invented certain new and useful Improvements in Block Systems, of which the following is a specification.

Our invention relates to a railway signaling mechanism designed for use in connection with the semaphore now commonly in use on railways.

The object of the invention is to provide a railway signaling mechanism which will give visual and audible indication that the road ahead is not clear, or conditions exist which require the train to slow up or come to a stop, the audible indication supplementing the visual; and to provide in addition, a positive means for bringing the train to a stop if the visual and audible warnings are disregarded. Our invention consists in the elements, combinations, and arrangements of parts all as will be hereinafter fully set forth and defined in the annexed claims.

In the accompanying drawings, which are to be taken as a part of this specification, Figure 1 is a perspective view of a section of track showing the arrangement of the several parts of the invention as in operative connection with the semaphore. Fig. II is a side elevation of a section of track, with a locomotive thereon, showing the means in connection with the track and locomotive respectively, for causing positive stoppage of the locomotive; and Fig. III is a sectional view through the automatic air valve and its casing.

Referring to the numerals of the drawing 1 indicates a locomotive, or other vehicle of a railway train, running upon the tracks 2.

3 indicates the standard of a semaphore signal, which is arranged adjacent to the railroad and provided at its upper end with a vertically swinging signal arm 4, which is shifted to indicate the condition of the railway ahead of a train. When this semaphore arm is in a pendent position, as indicated in dotted lines in Fig. I, it indicates that the road ahead is clear, but when the same is swung upwardly at right angles to a standard,

as shown in Fig. I, it indicates that for some reason the road ahead of the train is blocked. 55 The semaphore arm is operated preferably by lever connections hereafter described, actuated by hand, compressed air, electricity, or in any other suitable way. As illustrated the semaphore arm is operated by means of a 60 vertical rod 5, which is connected at its upper end with the heel or crank 6 of the semaphore arm, and which is raised or lowered by means of its connection at the lower end of a vertically swinging bell crank lever 7. Said bell 65 crank lever is in operative connection with a reach rod 8, which is in turn operated upon by compressed air or other actuating means not shown.

The semaphore just described comprises 70 the visible indicating means of our system. The audible signaling part of the mechanism which is in operative connection with said visual indicating means, has an operation bearing a distinctive relation to the 75 semaphore, and is constructed as follows:

9 represents an inclosed casing or housing, which is arranged adjacent to the railway track, on the same side thereof as the semaphore signal. As shown, for the sake of 80 securing rigidity, and to insure that the track shall not move independently of the housing, we prefer to make said housing in the form of a hollow extension of one of the ties. Reciprocating within said housing is 85 a link 10, pivoted at one end to the arm 11 of a bell crank lever pivoted to a member 12 adjacent the housing 9 and rigid with respect thereto. The other arm 13 of said bell crank lever is pivotally attached to the reach rod 8 90 as by means of an adjustable screw and collar or clamp connection 14. At its other end the said link 10 is pivoted to a carrier rod 15, which at its outer end is bent up as at 16 to project through a slot 17 in the upper face 95 of the housing 9. Said slot is arranged longitudinally of the housing and is long enough to permit the upturned end 16 to reciprocate therein for the purposes hereinafter set forth. Said end 16 is provided with a torpedo holder 100 18, upon which may be placed a detonating cap or torpedo which upon reciprocation of the link 10 may move into a position over or away from the adjacent track rail. Such reciprocation is brought about by movement 105 of the reach rod 8, the operating parts being

so positioned and adjusted that when the said rod 8 is moved to throw the arm 4 into danger position, the holder 18 will at the same time be projected into a position directly over the adjacent rail 2.

At some point on the line of railroad between the audible signal just described and the semaphore signal, we provide the means for effecting positive stoppage of a train in case the visible and audible signals are both disregarded. Such means comprise a housing 19 similar to housing 9, a link 20 similar to link 10 and having operative connections with the reach rod 8 similar to those described for the connection of link 10 with the rod 8. At its other end, the link 20 is pivotally connected to a trip lever 21 having an upwardly and forwardly bent end 22 adapted to travel within a slot 23 in like manner as the end 16 of rod 15. The end 22 is of such length that it cannot be projected over the adjacent rail 2, but is arranged so that it will extend a sufficient height above the level of the rail, and so that it may be brought sufficiently close to the side thereof to permit of its actuating a depending tappet 24 in operative connection with the air-brake mechanism. The positive stop mechanism just described is so relatively positioned and connected with the reach rod 8 as that the trip block 22 will be brought into tappet-actuating position when the semaphore arm 4 is in danger position.

25 represents a valve which is connected with the train pipe 26 in such manner that the opening or closing of this valve controls the operation of the brakes. This valve may be mounted on any suitable part of the locomotive, tender, coach or other part of the train, and its plug is connected with a horizontal shaft 27, extending transversely of the car. Said shaft 27 is provided at opposite ends with a depending tappet 24 arranged outside of the rail upon which the car wheels rest. The trip block 22 being movable transversely relatively to the tracks into and out of the path of the tappet 24 aforesaid, it will be evident the brake mechanism may be controlled by movement of the reach rod 8. In Fig. III we have shown a form of valve especially adapted for use in connection with this invention. As shown the plug 28 is of respectively much smaller diameter than the inner wall of its casing 29, except for a small portion of its periphery, indicated by the numeral 30 which extends outwardly approximately the full length of the radius from the center of the casing to the inner wall thereof. Said portion 30 is somewhat wider than the opening 31 in the valve shell which constitutes the exhaust port thereof. When the plug is in the position indicated in Fig. III, with its controlling tappet in the position shown in Fig. I, the valve is closed; and there is no operation

of the brakes whatsoever. If the tappet be actuated by the trip block 22 the part 30 of the plug will be moved to uncover the port 31, allowing an escape of air, and thus setting the brakes, according to a system in familiar use. Where the ordinary form of valve is used, comprising an apertured plug adapted to register with a port in the casing, it might happen that if the train were moving at a rapid rate of speed, the tappet would be struck with sufficient force to throw the plug around sufficiently to bring the valve to closed position again; but with the form of valve shown in Fig. III this is practically impossible, because when once the port 31 is uncovered, there is an escape for the air around the larger part of the periphery of the plug, and the tappet need not be moved any exact distance in order to bring about an exhaust. The operation of this interconnected mechanism is thought to be sufficiently clear from the detailed description of parts hereinbefore and further explanation will not be attempted except to say that the positive stop mechanism is positioned intermediate the visible and audible signaling means for a very specific reason to wit:

It has heretofore been purposed to position such a positive stop mechanism directly over a torpedo device. But this is a waste of valuable operations, inasmuch as there is absolutely no use in either the one or the other if they operate simultaneously. Whereas in our system, the audible signaling device gives a preliminary warning to slow up in case the semaphore signal has been disregarded. If thereupon the torpedo signal is disregarded, then the positive stop will come into effect, but the positive stop and torpedo mechanisms are sufficiently far apart, so that the train may be stopped if the torpedo signal is heeded without subjecting the train to the wear and tear of an emergency stop. Furthermore inasmuch as all of the various signals are operated simultaneously, if a train is stopped by means of the emergency stop, it will be an indication that the engineer failed to obey both the visible and audible signal, so that there is provided a positive means for fixing the blame for any carelessness or oversight.

What we claim is:

1. In a device of the character described, a visual signal and an audible signal in operative connection, and means adapted to co-operate with means upon a car for effecting positive stoppage thereof, said first-named means being located intermediate the visual and audible signals.

2. In a device of the character described, means moving a torpedo over a rail, means for operating a semaphore arm, said means being operatively connected and means intermediate said other means for acting upon a car to effect positive stoppage of the same,

said last - named means being operatively connected to the torpedo and semaphore mechanisms aforesaid.

3. In a device of the character described in combination, a semaphore arm, means for moving a torpedo over a rail, and means intermediate said semaphore and torpedo moving means for effecting positive stoppage of the train, and common means adapted to actuate said semaphore to the danger position, at the same time that the torpedo moving means is adapted to move a torpedo over a rail and a positive stoppage means is brought into operative position.
- 15 4. A device of the character described, a visual signal and an audible signal in operative connection, a trip block in operative connection with said visual and audible signal and intermediate the two adapted to be moved into position to actuate a depending tappet on a car, and a depending tappet on a car controlling a valve in operative and con-

trolling relation to the air brake system on a train.

5. In a device of the character described, a visual signal and an audible signal and a trip block in operative connection, a tappet controlled valve on a train adapted to actuate by said trip block to permit the exhaust of air from said valve, said valve comprising a casing, a plug within said casing, an arc shaped channel around the greater part of the perimeter of said plug, a port in said shell and an enlargement of said plug between the ends of said arc shaped channel adapted to close said port, substantially as set forth.

In testimony whereof we affix our signatures in presence of two witnesses.

CHARLES C. HARPER.
JOHN HARPER.
